7 Claims. (Cl. 339—5)

ABSTRACT OF THE DISCLOSURE

A brush and slip-ring assembly of inorganic composition, the slip-ring assembly including a plurality of identical disc-like elements stacked adjoining one another, each element being provided with a plurality of apertures and a preformed radial channel in the outer surface, the channel communicating with one of the apertures and the outer periphery of the element, the apertures of adjacent elements being in registration, a plurality of conductors free of organic insulation extending through the aligned apertures with one conductor extending through each radial channel, circumferential grooves at the junction of adjacent elements are provided with conductive contacting surfaces in electrical contact with the corresponding conductor, the brush assembly having one brush in contact with each conductive surface.

The present invention relates to rotating contact assemblies and, more particularly, to brush and slip-ring assemblies suitable for transferring electrical signals or electrical power between relatively rotating components such as are employed in precision instruments, for example, in gyroscopic guidance systems.

Of major importance in precision instruments, such as the gyroscopic systems used to perform indicating or control functions on modern, high speed aircraft or ships, is the low-noise transmission of low-level electrical signals to and from moving and rotating structures. A significant source of unwanted electrical fluctuations or noise in such apparatus is the variation in the resistance between the contacts in the brush and slip-ring assemblies. It has been determined that, when such brush and slip-ring assemblies employ base metal contacts, one cause of the variation in the resistance is due to an insulating oxide of the contact materials which forms on the contacts. Changes in the design of the brush and slip-ring assemblies to replace the base metal with precious metal contacts effectively eliminated the oxides, but failed to prevent the occurrence of the residual variations. Despite continuing efforts of the industry toward the improvement of the materials, processes and designs, the problem continues with only reductions in the magnitude of such resistance variations.

It has been determined that the high fluctuating resistance between the contacts in the brush and slip-ring assemblies is caused by collections of high resistance material in the contact area. The consensus is that the film forms from organic materials in the vicinity of the wiped precious metal contact. The contact material apparently reacts with, or catalyzes the polymerization of organic materials which reach the noble metal of the contact. The organic material can travel to the contact either as a liquid (from plastic wire insulation or from processing residues) or it can deposit on the contact by vaporized organics from the slip-ring insulating material. Once deposited on the metal contact, a reaction occurs and the organic begins to harden into a material of high electrical and chemical resistance. Such related problems cause inadequate contact life which necessitates frequent and expensive overhaul and repairs to maintain critical operational tolerances.

It is, therefore, an object of the present invention to provide sliding electrical contact assemblies capable of

2

reliable, low-noise performance for relatively extended periods of time.

It is another object of the present invention to improve the operation of sliding contact assemblies by eliminating all organic material therefrom.

Experiments heretofore conducted have pointed up certain difficulties that make brush and slip-ring assemblies fabricated of inorganic materials seem impractical. First, it has been thought that most glasses and ceramics cannot be formed around components since the working temperatures of glass and ceramic materials exceed working temperatures of the components. This is particularly true with the nonferrous components, such as those made of copper alloys (for example, the lead-in wire) and the gold alloy slip-rings. In the case of components manufactured of fired ceramic materials, the firing temperatures of the ceramics are not stable. Second, the ceramic industry has not been able to produce materials which can be cast, molded or fired to form components having precise dimensions. Most ceramic materials, due to shrinkage, change dimensions by a factor of several percent as the formed components cool. Third, because of the hard, abrasive nature of inorganic materials, heretofore it has been found difficult to cut grooves into such material to enable electrodeposition of the slip-rings.

Thus, another object of the present invention is to facilitate the fabrication of inorganic sliding contact assemblies having a longer useful life and no resistance variations between contact members therein.

These and other objects are accomplished in one embodiment of the invention by a sliding contact assembly wherein the slip-ring assembly consists of a supporting shaft on which preformed, high strength, glass wafers or discs are stacked. Each wafer is constructed of an inorganic material which has no out-gassing characteristics at elevated temperatures. Each of the preformed wafers has a plurality of holes cut therethrough parallel to the axis of rotation of the supporting shaft and which are oriented to be in register with corresponding holes in adjacent wafers. When the total number of wafers is stacked on the supporting shaft, a plurality of channels is formed. Through each of these channels an uninsulated lead wire is threaded from one end of the assembly to a respective outlet on a different one of the wafers. When the wafers have been properly oriented on the supporting shaft and the lead wires threaded therethrough, the assembly is heated to a temperature sufficiently high to cause the wafers to fuse to one another. A conductive slip-ring is formed on each wafer so as to be in conductive engagement with its respective lead wire.

Each brush assembly in the embodiment of the invention described herein is also fabricated of similar inorganic material having channels therein through which uninsulated lead wires are threaded to the points of connection to the brushes. The slip-ring assembly and the brush assemblies are enclosed within a housing which substantially prevents exposure of the brush and slip-ring contacts to contaminants of the external environment.

These and other advantages and features which are believed to be characteristic of the present invention, both as to its organization and method of operation, will be better understood from the following description considered in connection with the accompanying drawings in which one embodiment of the present invention is illustrated by way of example. It is to be expressly understood, however, that the drawings are for the purpose of illustration and description only and are not intended as a definition of the limits of the invention.

In the drawings:

FIGURE 1 is a cross-sectional view of a slip-ring capsule constructed in accordance with the teachings of the present invention;

FIGURE 2 is a partially sectional side view of a slip-ring and brush assembly which schematically illustrates the engagement of one with the other in a capsule of the type shown in FIGURE 1;

FIGURE 3 is a side view of a partially assembled slip-ring assembly showing slip-ring wafers in stacked relationship to one another having a lead wire protruding from each wafer;

FIGURE 4 is a first cross-sectional view of the slip-ring assembly shown in FIGURE 3 taken at the line 4—4;

FIGURE 5 is a second cross-sectional view of the slip-ring assembly shown in FIGURE 3 taken at the line 5—5;

FIGURE 6 is a vertical cross section of one typical slip-ring wafer showing longitudinal holes and a radial groove cut in the wafer;

FIGURE 7 is a sectional view of one slip-ring showing the formation thereof on a corresponding slip-ring wafer;

FIGURE 8 is a bottom view of one brush assembly shown in FIGURE 2; and

FIGURE 9 is an end view of the slip-ring and brush assembly shown in FIGURE 2.

Reference is now made to the drawings, wherein like or corresponding parts are designated by the same or similar reference characters throughout the several views. There is shown in FIGURE 1 a slip-ring capsule 10 having a housing 11 which surrounds an inorganic slip-ring assembly 12 and a pair of inorganic brush assemblies 30 and 33. The slip-ring assembly 12 consists of a supporting shaft 15 which carries a plurality of conductive slip-rings 16. The shaft 15 may be fabricated, for example, from stainless steel. Each conductive slip-ring 16 is connected respectively to a wire 40 which is uninsulated and threaded through a hole in the slip-ring assembly running from its point of connection to slip-ring 16 to a slip-ring reinforcing member 13. Within the slip-ring reinforcing member 13 the wires 40 are connected respectively to insulated slip-ring lead wires 44 for attachment to sources of electrical signals or power. A detailed description of the construction of the slip-rings 16 will be undertaken herein-after in connection with FIGURES 2 and 3.

As shown in FIGURE 1, the slip-ring assembly 12 is rotatably supported within the housing 11 by a pair of bearings 20 and 21. A frame member 28 holds the bearings 20 and 21 in their proper position within the housing 11, such that the bearings engage with a pair of bearing seats 14 and 17, respectively, which are mounted on the supporting shaft 15. One end of this supporting shaft 15 has been reduced in diameter and threads 27 placed thereon. A nut 23 is threaded on to the threads 27 for urging against a bearing retaining ring 24 which, as the nut 23 is tightened, properly seats the bearing 21 on the bearing seat 17. It will be noticed that the shaft 15 has been reduced in size at location 25 to allow proper clearance for the bearing retaining ring to mate with bearing 21. The bearing seat 14, located at the opposite end of the slip-ring assembly 12 from the bearing seat 17, is simultaneously positioned with respect to its corresponding bearing 20 as the nut 23 is tightened on the threads 27.

The supporting shaft 15 which passes through the bearing seat 14 terminates in the slip-ring reinforcing member 13. To secure the shaft within the reinforcing member and to provide insulation between the uninsulated lead wires 40, at their point of connection 42 to the slip-ring lead wires 44, the void within the slip-ring reinforcing member 13 is filled with a solder glass 18 or Pyroceram Cement No. 95 manufactured by the Corning Glassworks of Corning, N.Y.

The brush block assemblies 30 and 33 are secured in position by the retaining screws 31 and 34, respectively. As may be understood from the description which herein-after follows, a plurality of brushes 60 of the brush assembly 30 and a plurality of brushes 61 of the brush assembly 33 slideably engage with, and receive signals from, the conductive slip-rings 16. These signals are transmitted

from the brushes 60 and 61 through lead wires 62 and 63, respectively, to utilization devices therefor.

Attention is now directed to FIGURE 2 wherein there is shown a partially sectional side view of the slip-ring assembly 12 and the pair of brush assemblies 30 and 33 forming a part of the slip-ring capsule 10, shown in FIGURE 1. In accordance with one aspect of the invention, the brush assembly 33 is shown in FIGURES 2, 8 and 9 to include an insulating member 37, having a support member 38 attached to one end thereof. The lead wires 63 terminate within the support member 38 and are connected to a plurality of conductors 65. Channels cut in the top of the insulating member 37 are filled with copper, or silver, or gold alloy with a copper coating to form junction bars 59, and one of the conductors 65 is attached to each of the filled junction bars 59. The brushes 61 are then soldered to the junction bars 59 such that each brush 61 wraps around the insulating member 37 (as shown in FIGURE 8) and slideably engages with one of the slip-rings 16 (as shown in FIGURES 2 and 9).

The brush assembly 30, which is shown in FIGURES 2 and 9, is constructed similar to the brush assembly 33 to include an insulating member 35 having a support member 36 attached to one end thereof. The insulating members 35 and 37 together with their respective support members 36 and 38 may be constructed of a number of inorganic materials, such as Fotoceram, a trademark for a high strength glass of the Corning Glassworks of Corning, N.Y. The brush assembly 30 is shown in FIGURE 2 to have a plurality of junction bars 58 to which the brushes 60 are soldered. A corresponding plurality of conductors 64 couple the junction bars 58 to the brush block leads 62, the insulation of the brush block leads 62 terminating within the support member 37 of the brush assembly 30. Alternatively, the brushes 60 and 61 may be cast into the brush blocks at the time the brush blocks are formed. Thus, no organic materials, such as those used for wire insulation and heretofore for brush blocks, are used in the area of contact between the brushes and slip-rings.

Attempts to manufacture slip-ring and brush assemblies using glass or ceramic materials heretofore have been unsuccessful because of the acute problems associated with machining and handling the glass or ceramic materials, holding the required dimensions of components manufactured from such materials, and with the high temperatures at which glass or ceramic materials are fired or worked. These problems have restricted, and in most cases precluded, the use of glass or ceramic in brush and slip-ring assemblies.

However, in recent years, form-grinding techniques have been perfected to the point where they may be applied to solve the problem of machining glass and ceramic materials for use in slip-ring assemblies. Thus, directing attention to FIGURES 2 through 6, and in accordance with another aspect of the present invention, the slip-ring assembly 12 comprises a number of discs, or wafers, 50 fabricated of inorganic material, such as Fotoceram glass, and stacked on and attached to the supporting shaft 15. A typical wafer, as shown in FIGURES 5 and 6, is fabricated to have a number of longitudinal holes 46 formed or chemically machined through the glass wafer 50 parallel to the axis of rotation of the supporting shaft 15. A number of wafers 50 are stacked on the supporting shaft 15 and oriented so that the holes 46 of each wafer are in register to form longitudinal channels through which lead wires 42 may be threaded. The number of longitudinal holes 46 which are cut through each wafer 50 corresponds to the number of slip-rings 16 to be included in the slip-ring assembly 12. Moreover, as shown in FIGURES 5 and 6, a radial groove 51 is cut or formed from one of the longitudinal holes 46 (such as the radial groove 51 connected to a longitudinal hole 48) to the outer circumference of the wafer. One lead wire of the plurality of lead wires 42 (such as a lead wire 45 passing through the

hole 48) is threaded through corresponding ones of the longitudinal holes and then bent so as to exit the stack of wafers 50 through one of the radial grooves 51.

Glass spacing wafers 54 are positioned on one side of the stack of slip-ring wafers 60; and, on the other side of the stack of slip-ring wafers 50, an insulating wafer 52 (having a corresponding number of longitudinal holes 46 cut therein) is positioned on the shaft 15 such that the longitudinal holes 46 therein will be in register with the longitudinal channels formed by the stack of wafers 50. Once the wafers 50, 52, and 54 are stacked on the supporting shaft 15 and oriented to have the lead wires 42 (including the lead wire 45, for example) passing through the longitudinal channels, the assembly is heated to a temperature of approximately 800° centigrade in order to fuse the wafers together. Alternatively, the assembly could be sealed with solder glass of Pyroceram Cement No. 95 manufactured by the Corning Glassworks of Corning, N.Y. Pyroceram Cement may also be used, for example, to attach the glass wafers to the shaft 15.

Thus, by either heating or coating the stacked slip-ring wafers with solder glass or Pyroceram Cement, the wafers 50, 52 and 54 are joined to form essentially one homogeneous mass through which each of the lead wires 42 extend from one end of the stack to its respective radial groove 51. For example, FIGURE 5 illustrates a cross-section of the partially-assembled slip-ring assembly 12 taken at the line 5—5 of FIGURE 3. It may be seen that the lead wire 45 has been threaded through the bearing seat 14, the wafer 52, and through each of the wafers 50 to the location of the last wafer 50 in the stack. The lead wire 45 is threaded up through the radial slot 51 in the last wafer 50.

To form the actual slip-rings 16, then, circumferential grooves are ground into the outer surface of the fused glass wafers with a spacing between grooves such that an end of one lead wire 42 is exposed in the bottom of each groove. With reference to FIGURE 7, for example, in order to form one of the slip-rings 16, the end of the lead wire 45 has a small amount of copper electro-formed thereon. Next, a thin layer of electroless copper is reduced into the groove. More copper is plated on top of the electroless copper. A layer of metal, such as nickel, is electroformed or deposited on the surface of the assembly and into the circumferential groove to a depth of less than ten millionths of an inch. The thin layer of nickel is then removed everywhere except in the bottom of the groove by any one of a number of well known methods, such as grinding. Gold is then electrodeposited on the thin nickel layer in the bottom of the groove until the groove is filled with gold. The surface of the slip-ring assembly is ground to remove the excess gold and a thin layer of glass, thereby making the slip-rings flush with the adjoining glass surfaces. A V-groove 56 is cut into the deposited gold to form a slip-ring of the type described and claimed in the copending application of James Carl Davis for Multitrack Slip-Rings, Ser. No. 434,976.

Although the invention is illustrated in the embodiment of FIGURES 2 and 7 having a particular electrodeposited construction with a V-shaped groove or channel therein, it will be appreciated that other metals and channels having other cross-sections which are wider at the top and narrower at the bottom may also be used. Yet other types of channels adapted to receive a brush in sliding conductive contact with the channel walls may also be employed, such as channels which vary arbitrarily over their depth from a maximum to a minimum width.

Miniature brushes of the type employed in the present invention, such as the brushes 60 and 61 shown in FIGURE 2, may be fabricated from a gold alloy material sold under the trade name of Meyoro 28A, produced by the J. M. Mey Company of Broomfield, Conn. It has been found that by employing both a precious metal (gold) slip-ring 16 and a set of precious metal brushes 60 and 61, the most frequently noted failures in slip-ring assem-

blies, due to the formation of insulating oxides, can be eliminated. Moreover, by employing the totally inorganic construction technique of the present invention, which eliminates the use of all organic materials from the inside of the slip-ring capsule 10, additional improvements in the operation of the brush and slip-ring assembly are obtained.

To obtain even greater reliability in the operation of the precision slip-ring capsule 10, each of the brushes 60 and 61 (which may also take the form of a formed brush 57, shown in FIGURE 7) makes contact with its respective slip-ring 16 at two locations spaced approximately 180° apart. Such an arrangement (shown in FIGURES 2 and 9) provides four contact areas, two for each brush, with the V-groove of the slip-ring 16; and, because inorganic materials have been effectively eliminated from the inside of the slip-ring capsule 10, the assembly operates with significantly less electrical noise caused by fluctuations in the contact resistance. Moreover, by minimizing the exposure of the contacts to contaminating organics from the capsule assembly itself, and by minimizing the exposure of the contacts to environments external to the capsule so that no gas flow can occur through the assembly, the only contaminants which reach the contact surfaces are those attributable to air flow into the capsule as a result of a "breathing" action, which is less likely to represent a serious source of contaminants.

It is to be understood that the above-described arrangements are illustrative of the application of the principles of the invention. Numerous other arrangements may be devised by those skilled in the art without departing from the spirit and scope of the invention. Thus, by way of example and not of limitation, brushes and grooves of various sizes and cross-sectional configuration may be employed to achieve multi-track contact as taught herein by example. Additionally, other inorganic materials having characteristics comparable to those of Fotoceram glass may be used to fabricate the insulating base for the electroformed slip-rings. Accordingly, from the foregoing, it is evident that various changes may be made without departing from the spirit of the invention as defined in the appended claims.

What is claimed as new is:

1. A sliding contact assembly comprising:
a plurality of inorganic disc-like elements, each of said elements being identical in size and configuration and being provided with a plurality of apertures extending therethrough and a radial channel in the outer surface thereof, said channel communicating with one of said apertures and the outer periphery of said element, said elements being stacked adjoining one another with the apertures thereof in registration with apertures in the adjoining element;
a plurality of conductors free of organic insulation extending through the registered apertures with one of said conductors extending through each said radial channel to the outer periphery of the corresponding element;
circumferential grooves on the periphery of said elements adjacent the junction of adjoining elements, each of said grooves having at least one of said conductors communicating therewith; and
conductive contacting surfaces within said grooves in electrical contact with the corresponding conductor.
2. The sliding contact assembly as defined in claim 1, wherein said plurality of disc-like elements are ceramic and are inorganically bonded together to form essentially a homogeneous cylinder.
3. The sliding contact assembly as defined in claim 1, wherein said plurality of disc-like elements are ceramic and are fused together to form essentially a homogeneous cylinder.
4. The sliding contact assembly as defined in claim 1, which further includes:
an inorganic brush block positioned adjacent said stacked elements and having a plurality of brush

- block conductors free of organic insulation threaded therethrough; and
- a plurality of noble metal brushes supported by said brush block and respectively connected to said brush block conductors, each of said brushes being in sliding conductive contact with a separate one of said contacting surfaces.
5. The sliding contact assembly as defined in claim 1, which further includes:
- a rotatable support member, said plurality of disc-like elements being affixed to said support member.
- 10
6. A method of making a sliding contact assembly, including the steps of:
- preforming a plurality of disc-like elements from inorganic material to have a radially extending channel 15 in the outer surface thereof;
- stacking said elements on a supporting member so that they are contiguous with one another with each of said channels engaging the surface of an adjoining element to form a radial aperture;
- 20
- threading conductors free from organic insulation through respective apertures with the ends of said conductors terminating at least adjacent to the periphery of the corresponding element;
- inorganically bonding the stack of disc-like elements to 25 form a rigid cylinder;
- grinding circumferential grooves in the periphery of said elements to remove a portion of the ends of said conductors; and
- forming conductive contacting surfaces within said 30 grooves in electrical contact with respective conductors.

7. A method of making a sliding contact assembly as set forth in claim 6 which further includes the steps of:
- forming said disc-like elements to be identical and to have a plurality of holes through each element, each of said channels communicating with one of said holes and the periphery of its corresponding element;
- orienting said elements so that said plurality of holes are in register to form a corresponding plurality of longitudinal apertures through the stack of elements with a different one of said channels extending from each longitudinal aperture;
- threading said conductors through respective longitudinal apertures, one end of each conductor being threaded out through a corresponding radial channel; and
- fusing the stack of disc-like elements to form a rigid cylinder.
